Primary Examiner — Richelle G Shelton(74) *Attorney, Agent, or Firm* — Banner & Witcoff, Ltd.(57) **CLAIM**

The ornamental design for a display screen with graphical user interface, as shown and described.

DESCRIPTION

FIG. 1 is a front view of a display screen with graphical user interface showing our new design; and,
 FIG. 2 is a front view of the display screen with graphical user interface of FIG. 1, shown without broken line detail.
 The broken line showing of the display screen and remainder of the graphical user interface is for environmental purposes only and forms no part of the claimed design.
